NEUROLOGICAL DIAGNOSTIC INSTRUMENT

William E. Marsh, 975 Overlook Road,
Berkeley, Calif. 94705

Filed Aug. 2, 1966, Ser. No. 3,314

Term of patent 14 years

(Cl. D83—12)

FIG. 1.

FIG. 2.

Fig. 3.Fig. 4.

FIGURE 1 is a front elevation of a neurological diagnostic instrument, showing my new design;

FIGURE 2 is a bottom plan view thereof;

FIGURE 3 is a rear elevation thereof; and

FIGURE 4 is a top plan view thereof.

I claim:

The ornamental design for a neurological diagnostic instrument, as shown.
